SMOKER'S PIPE CLEANER

George C. Dickey, San Francisco, Calif.

Application May 26, 1943, Serial No. 488,514.

7 Claims. (Cl. 131—246)

This invention relates to devices for cleaning out the encrusted bowl of smokers' pipes, and the principal object of the invention is to provide improvements in such devices which will make the device more serviceable.

Other objects and advantages of the invention will appear in the following description and in the accompanying drawing.

In the drawing:

Fig. 1 is a perspective view of my improved pipe cleaner ready for use.

Fig. 2 is a side view of the device with its lever locking cap removed, also its layer of abrading paper or "emery cloth" taken off, and its wire clamping lever opened out to extend at right angles to the core or body of the device.

Fig. 3 is a side view of the lever locking cap.

Fig. 4 is a plan view of a modification of the emery cloth or sand paper used around the core of the device.

Fig. 5 is an enlarged cross section of Fig. 2 as seen from the line 5—5.

Fig. 6 is a perspective view of a double ended abrader made in tubular form.

Before describing the drawing in detail, it may be said that the device is a pipe bowl cleaner of the type having a rigid core with a sheet or tube of emery cloth or sand paper wrapped about it so as to enable it to be twisted back and forth in the bowl of the pipe to grind out the caked and encrusted matter. The invention has mostly to do with the application of the abrading material to the core, whereby the operation of the device is facilitated and improved. A feature of the device is that it also provides means for cleaning out the bore in the stem of the pipe.

In further detail the device comprises an elongated round plug or core 1 preferably of wood, and of a diameter somewhat smaller than the average interior of a smoker's pipe bowl, and the plug is rounded at one end as at 2, while along one side of the plug is a V shaped shallow groove 3 which joins a short narrow slot 4 which extends deeper into the plug and terminates at 4' so as to leave the lower end of the plug, from 4' down, solid and unyielding.

Transversely pivoted by a pin 6 in a slightly widened portion of the slot is a wire lever 7 adapted to swing from a position extending substantially at right angles with the plug, as shown in Fig. 2, to a position within the shallow groove 3, for the purpose of clamping an abrasive sheet 8 around the plug, and to be locked in clamping position by any suitable means, but here indicated as a thin hollow cap 9 which slides down

over the upper ends of both the plug and the wire—as shown in Fig. 1.

The abrasive sheet may be sandpaper or emery cloth, preferably the latter, and it is preferably formed to the shape shown in Fig. 4. The sheet 8 is substantially rectangular but with V shaped serrations 10 formed along opposite edges of a size to fold down snugly together to fit around and cover the rounding end 2 of the plug when the sheet is wrapped around it. The object of having the serrations on both edges of the sheet is to make the sheet reversible on the plug, tho the sheet need have but one edge serrated if the reversible feature were not desired, and such a sheet is shown in place on the plug in Fig. 1 and whereon the abrasive material is indicated at 12.

To hold the abrasive sheet firmly in position it is provided with a pair of tongues 13, 14, the latter of which is somewhat longer than the former, so that in applying the sheet, the wire lever 7 is opened to the position shown in Fig. 2, the longer tongue 14 of the sheet 8 is pushed into the snugly fitting slot or kerf 4, the sheet is wound about the plug, and which will bring the smaller tongue in overlying position with the longer one, as clearly indicated in Fig. 5, and with the wrapped sheet held with the fingers of one hand the wire lever 7 is swung into the groove 3 to clamp the two overlying tongues or extensions 13, 14 and also draw the sheet very tightly about the plug. The cap 9 is then pushed over the end of the plug to lock the wire lever in place, and the serrations 10 are folded down smoothly over the rounded end of the plug.

In using the device, the plug is grasped about the upper portion with the fingers preferably extending somewhat over the abrasive sheet as well, and the rounded end of the plug is inserted into the pipe bowl and pressed against the side of the bowl and given a rotary twist while the bowl is preferably slowly turned.

Since the plug is cylindrical and somewhat smaller than the bowl it cannot become wedged into the bowl, and may be effectively used with any size pipe larger than the plug. Also as the plug is rigid and unyielding it permits a hard contact to grind off the encrusted material in the bowl of the pipe.

A further feature of the device is that the wire lever 7 when extended as shown in Fig. 2 provides the means for cleaning out the smoke passage at the base of the bowl and also the passage in the stem of the pipe. The extreme end of the wire is purposely left with a sharp corner at 7' for this purpose.

As a modification in the form of abrasive sheet, the sheet may be pre-fabricated as a complete tube of a size to nicely fit over the plug by sliding it thereover. Such a tube is shown in Fig. 6 at 6' and is also indicated with the V shaped serrations 10 at both ends. The tube is longitudinally slotted for a short distance through one side as indicated at 15 so that when pushing it down over the plug from above with the wire extended as in Fig. 2, the slot will embrace the wire and form a stop when the tube is down far enough. The details of forming the abrasive tube are unimportant as it may have an overlapping joint or be formed seamless, and may be of paper, cloth, or of any flexible sheet material such as the various cellulosic and plastic sheets on the market, and the abrasive material may be secured all over its outer surface in the known way of holding the sand or emery in place on sand and emery papers.

As a modified use, the tube form of abrasive covering may be slipped over the plug with its wire 1 already seated in its groove 3, and the plug and upper portion of the tube gripped to apply the grinding or reaming action in cleaning a pipe bowl. It is obvious that the serrations 10 may be omitted from one end of the emery cloth tube as shown for the emery cloth wrapping 8 of Fig. 1, but that the tube would not then be reversible end for end.

Having thus described my improved pipe cleaner, what I claim is:

1. A device for cleaning smokers' pipes comprising a round elongated plug of a size to enter the bowl of the pipe, a flexible sheet of abrasive material around said plug, and clamping means for drawing said sheet taut about said plug and holding it in place, said plug being solid and rounded at its lower end, and said sheet of abrasive material being formed with V shaped serrations along one of its edges of a form and size to fold down over the rounded end of the plug.

2. In the combination as set out in claim 1, said sheet of abrasive material being serrated at

opposite ends so as to be reversible on said plug.

3. A device of the character described comprising an elongated round plug with one end solid and rounded, a groove along the side of the plug, a wire lever pivoted at one end to the plug adjacent but spaced from the solid rounded end in a manner to lie wholly in the side groove to clamp a sheet of emery cloth about the plug or swing out of the groove to a position extending laterally

10 from the plug, and means for locking the wire lever in place when in the groove.

4. In a structure as set out in claim 3, said groove being deepened adjacent the rounded end of the plug in the form of a narrow slot to receive an extension of the emery cloth, and the means for locking the wire lever comprising a collar fitting over the end of the plug and freely slidably longitudinally over the free end of said wire lever.

20 5. In a smoker's pipe cleaner having a manually operable reaming plug with a rounded end, an abrasive covering for said plug comprising a flexible sheet of abrasive covered material of a size to surround said plug and provided with V shaped serrations adapted to fold around and cover the rounded end of the plug.

6. In a smoker's pipe cleaner having a manually operable reaming plug with a rounded end, an abrasive covering for said plug comprising a flexible sheet of abrasive covered material of a size to surround said plug and provided with V shaped serrations adapted to fold around and cover the rounded end of the plug, said serrations being on opposite edges of the sheet to provide for reversing the sheet on said plug.

30 7. In a smoker's pipe cleaner having a manually operable reaming plug with a rounded end, an abrasive covering for said plug comprising a flexible sheet of abrasive covered material pre-formed into a tube of a size to surround said plug and provided with V shaped serrations adapted to fold around and cover the rounded end of the plug.

GEORGE C. DICKEY.
